(57) **CLAIM**

The ornamental design for a filter block for liquid filtration, as shown and described.

DESCRIPTION

FIG. 1 is a front perspective view of the invented design for a filter block for liquid filtration.

FIG. 2 is a front view of the filter block of FIG. 1, with the back view being the same as front view.

FIG. 3 is a side view of the filter block of FIG. 1, with right and left side views being the same.

FIG. 4 is a top view of the filter block of FIG. 1.

FIG. 5 is a bottom view of the filter block of FIG. 1.

FIG. 6 is a cross-sectional, side view of the filter block of FIG. 1 taken along 6—6 in FIG. 4, the cross-section being taken axially front-to-back through the center of the filter block, and wherein stippling indicates the cut surface.

FIG. 7 is a cross-sectional, perspective side view of the filter block of FIG. 1 taken along 7—7 in FIG. 1, the cross-section being taken axially front-to-back through the center of the filter block, and, therefore, FIG. 7 being a perspective view of FIG. 6; and,

FIG. 8 is a cross-sectional, perspective front view of the filter block of FIG. 1 taken along 8—8 in FIG. 1, the cross-section being taken axially side-to-side through the middle of the filter block, and wherein stippling indicates the cut surface.
